UNITED STATES PATENT OFFICE.

VINCENT LEONARD CACCESE, OF ASBURY PARK, NEW JERSEY.

SEARCHLIGHT.

1,318,263.

Specification of Letters Patent.

Patented Oct. 7, 1919.

Application filed December 12, 1918. Serial No. 266,453.

To all whom it may concern:

Be it known that I, VINCENT LEONARD CACCESE, a citizen of the United States, and a resident of Asbury Park, in the county of 5 Monmouth and State of New Jersey, have invented a new and Improved Searchlight, of which the following is a full, clear, and exact description.

This invention relates to high powered 10 searchlights and has particular reference to the construction of such a device as contemplates not only maximum illuminating power, but also means to prevent damage due to excessive heat.

15 With the foregoing and other objects in view the invention consists in the arrangement and combination of parts hereinafter described and claimed, and while the invention is not restricted to the exact details 20 of construction disclosed or suggested herein, still for the purpose of illustrating a practical embodiment thereof reference is had to the accompanying drawings, in which like reference characters designate the same 25 parts in the several views, and in which

Figure 1 is a vertical longitudinal section showing a preferred embodiment of my improvement.

Fig. 2 is a smaller diagrammatic side elevation showing the exterior appearance of 30 the construction.

Fig. 3 is a view of the same character as Fig. 2 but showing the multi-part casing swung open.

35 Fig. 4 is a front elevation corresponding to the view of Fig. 1.

Fig. 5 is a vertical transverse section on the line 5—5 of Fig. 1; and

Fig. 6 is a detail view on the line 6—6 of 40 Fig. 5.

Referring now more specifically to the drawings I show a construction for high powered searchlights involving a casing shown in this instance as comprising three 45 main parts 10, 11, and 12, the several parts of the casing being arranged to accommodate independent lamps or a series of lamps, and each part of the casing furthermore constituting reflecting means for either its own 50 lamps or those of other sections.

Section 10 is or may be formed in a general way similar to an ordinary parabolic reflector, having a curvature somewhat less than a hemisphere and provided with a 55 single socket 13 for the accommodation of

a large and powerful lamp 14 arranged directly in the focal axis of the reflector.

The casing section 11 may be described as being of short cylindrical or tubular structure, the diameter of which conforms to the 60 largest diameter of the section 10 to which it is movably connected as through a hinge 15. A catch 16 of any suitable nature arranged opposite the hinge 15 serves to lock these two parts from movement around the 65 hinge. The section 11 is so constructed as to accommodate a circular series of lamps 17 all having their bases lying in the same plane perpendicular to the focal axis of the reflector 10 and secured in sockets 18. These 70 sockets are preferably arranged with their axes all lying in the same plane and radial with respect to said focal axis.

The third and outermost casing section 12 75 may be of any suitable form for best reflecting results, but illustrated as being approximately frusto-conical and having its smaller or inner end abutting against the outer end of the tubular section 11 and to which it is movably attached by means of a 80 hinge 19 at one side and provided with a catch 20 on the opposite side. The flaring section 12 carries a circular series of lamps 21 which may be similar to the lamps 17 or 85 larger and all arranged in substantially the same transverse plane although the sockets 22 for these lamps 21 have their axes perpendicular to the adjacent side walls of the section 12, and hence not radial as are the sockets 18 with respect to the focal axis of 90 the reflector.

These lamps are necessarily of high candle power and voltage and consequently an enormous amount of heat is developed thereby. In order to prevent overheating of the 95 casing or reflector as a whole, I provide for the several lamp bases and sockets extra large openings through the casing walls, such openings being indicated at 23, 24, and 25 for the respective casing sections. Surrounding the socket 13 and the opening 23 I provide a casing extension or hood 26 having a suitable number of air holes 26' formed through its side walls to insure ample circulation of air. The sockets 18 100 and openings 24 likewise are guarded by a casing extension or hood 27 having along its rear wall a wide open slot or air space 27'. A similar hood 28 having a wide open air slot 28' surrounds the sockets 22 and draft 110

openings 25 in the flaring casing section 12. These hood structures in either the tubular form at 26 or the annular forms at 27 and 28 serve to insure free cooling circulation 5 of air through the casing and around the lamps, and yet prevent any glare of light emerging through any portion of the casing except from the front as intended.

As above premised the interior surfaces 10 of the casing sections are all made of a reflecting nature. Any suitable means may be provided to carry out this purpose. Suffice it to say, therefore, that all of the exposed interior surfaces of these sections are 15 reflectors. Referring, however, more specifically to sections 11 and 12 it will be noted that I provide a pair of collars or rings 29 and 30 fixed to the inner walls of these sections respectively and abutting against each 20 other in a plane perpendicular to the focal axis of the reflector and substantially in the plane of the joint between the sections 11 and 12. The ring 29 may be described, therefore, as having a cylindrical outer surface, a flat front surface, and a concave 25 inner surface. The concave surface is a reflector and is directed toward the series of lamps 17 adjacent to which said lamps are fixed. The outermost ring 30 may be described as having a frusto-conical outer surface abutting against the inner wall of the flaring section 12, the flat rear surface against the flat front surface of the ring 29, and a concave front surface adjacent to 30 which the lamps 21 are located. Furthermore these two rings have registering central circular openings 31 and 32 respectively of sufficient capacity to permit the light from the lamp 14 to emerge in a strong beam 35 parallel to the focal axis of the structure and the diverging rays of light from lamps 17. The major portion of the light from the lamps 21 is caused to emerge directly from the front concave surface of the ring 40 30 and the flaring reflecting surface of the section 12, although a portion of the light from these lamps may be reflected from the

parabolic reflector 10. Any suitable wiring devices may be employed within the skill of an electrician that will supply current to 50 the several lamps.

I claim:

1. In a searchlight, a multi-part casing, one part being parabolic and having a lamp at its focus, the front parts being of different 55 shape from the first mentioned part, a circular series of lamps arranged in each of the other parts, and reflecting means serving to cause the light from the lamps to be thrown forward in a solid beam parallel to the 60 axis of the first mentioned casing part and in rays diverging from said axis.

2. The herein described searchlight comprising a casing having three parts, the rearward part being parabolic and having a lamp in its focus, the second part being cylindrical, a series of lamps supported in the second part with their bases projected radially outward through the wall of the cylindrical section, a reflecting ring adjacent 70 to the said series of lamps and arranged in front thereof and acting to cause the light from the lamps to be reflected inward to the first mentioned section and thence outward through the center of the ring, a 75 third conical part, a series of lamps arranged around the conical part, arranged to have their light reflected outwardly by the conical part, and means to secure the three parts of the casing together. 80

3. In a searchlight, the combination of a casing, the rear end of which is parabolic, a lamp fitted at the focus of the parabolic portion, two circular series of lamps arranged in parallel planes perpendicular to 85 said axis and located in the front portions of the casing, and reflecting means carried by said front portions of the casing to cause the light from the lamps to be thrown forward in a solid beam parallel to the axis of 90 the casing and in rays diverging from the axis.

VINCENT LEONARD CACCESE.
